ORNAMENTATION OF WATCH CASES.

No. 18,709.

Patented Oct. 30, 1888.

UNITED STATES PATENT OFFICE.

CHARLES H. PFEIL, OF CHICAGO, ILLINOIS, ASSIGNOR TO PFEIL, WILLIAMS & BREDT, OF SAME PLACE.

DESIGN FOR THE ORNAMENTATION OF WATCH-CASES.

SPECIFICATION forming part of Design No. 18,709, dated October 30, 1888.

Application filed August 20, 1888. Serial No. 283,264. Term of patent 3½ years.

To all whom it may concern:

Be it known that I, CHARLES H. PFEIL, a citizen of the United States, residing in Chicago, Cook county, State of Illinois, have invented and produced an original Design for the Surface Ornamentation for the Lid of a Watch Case, of which the following is a specification, reference being had to the accompanying illustration, forming a part thereof.

10 The illustration herewith presented shows a side elevation of the watch-case A with my design for the lid B.

The leading features of my design consist of a crescent, C, formed of two claws, c c', which are united at their bases by a keystone form, D, which consists of the face of a woman, d, having an Egyptian head-gear, d'. On either side of the face is a band extending from the outer to the inner edge of the crescent, each band having a series of jewels on its face. The claws and face are slightly raised above the surrounding surface of the lid. Beneath the center of the crescent and suspended from its center is a Turkish cimeter, E, which falls 5 within the contour of the crescent. From the cimeter is suspended a five-point star, F, hav-

ing on its face a number of jewels. Beneath the star, above the Egyptian head or face and on either side of the crescent, are small rosettes e, composed of several elliptical-shaped leaves 30 grouped about a flower having scalloped edges. Surrounding the figures described, which constitute the leading features of my design, is a border, G, composed of circular lines, the continuity of which is broken to form a Grecian 35 border. The space within these lines and the milled periphery of the lid is filled with feather-work f.

What I claim is—

The design for the surface ornamentation of 40 the lid of a watch-case herein shown and described, the same comprising the crescent formed of two claws, the Egyptian head flanked by ornamental bands, the keystone shape having suspended therefrom a Turkish cimeter, and 45 a five-point star, the whole surrounded by rosettes and border, substantially as set forth.

CHARLES H. PFEIL.
